DESIGN FOR A COMBINED SUN VISOR AND SHIELD

Ivan P. Schmid, Columbus, Nebr.

Application January 11, 1943, Serial No. 109,232

Term of patent 14 years

To all whom it may concern:

Be it known that I, Ivan P. Schmid, a citizen of the United States, residing at Columbus, in the county of Platte and State of Nebraska, have invented a new, original, and ornamental Design for a Combined Sun Visor and Shield, of which the following is a specification, reference being had to the accompanying drawing, forming a part thereof.

I claim:

The ornamental design for a combined sun visor and shield, substantially as shown.

IVAN P. SCHMID.
